UNITED STATES PATENT OFFICE.

WILLIAM C. FORD, OF BROOKLYN, NEW YORK.

IMPROVEMENT IN APPARATUS FOR SUPERHEATING AIR FOR MARINE-BOILER FURNACES.

Specification forming part of Letters Patent No. 170,163, dated November 23, 1875; application filed September 29, 1875.

To all whom it may concern:

Be it known that I, WILLIAM C. FORD, of the city of Brooklyn, in the county of Kings, in the State of New York, have invented certain new and useful Improvements in the Method of Applying Superheated Air to the Furnaces of Marine Boilers; and I do hereby declare the following to be a full, clear, and exact description of the same, reference being had to the annexed drawing, making part of this specification, in which—

Figure 1 is a vertical section through the smoke-stack, steam-drum, and the fore part of two opposite boilers, showing the smoke and steam connections, and a vertical section through a furnace of each boiler, with my invention applied thereto. Fig. 2 is a vertical section through Fig. 3, on the line X X. Fig. 3 is a horizontal section, taken on the line Y Y of Fig. 1; and Fig. 4 is a horizontal section through the furnace above the grate-bars.

The object of this invention is to more effectually introduce and diffuse a current of superheated air in the furnace of a marine steam-boiler, upon the top of the fire, near the surface thereof, for the purpose of intensifying the surface of the fire, by obtaining a more perfect combustion of the fuel, through the intermingling of the fresh or free hot air with the inflammable gases at the surface of the fire.

My invention consists of a pipe, or a series of pipes or flues, combined with the smoke-stack or steam-chimney, and arranged in the fire or smoke flue, and connected to a jet-pipe, or a series of jet-pipes, to deliver the hot air upon the surface of the fire at the sides or in the front part of the furnace, the pipes or flues to be so arranged with reference to the smoke-flues and fire-surface as to heat the air upon its passage through the pipes by the escaping heat of the furnace.

An application of this invention is illustrated by the drawing, where A A represent two boilers, set opposite each other to leave a passage-way between them, the fronts of the boilers being turned toward each other to bring the furnaces on each side of the passage-way. The furnaces are shown by F F. The two boilers are connected overhead by means of a

steam-chimney, B, and a smoke-connection, H. The steam-chimney is arranged on the top of the smoke-connections, and is connected to the steam-space of the boiler by means of pipes or flues C C. On the top of the steam-chimney is arranged the smoke-stack D, large enough to embrace all the flues b b b in the steam-chimney. These are the ordinary parts of the marine boiler and its connections now in common use. The additions by which my invention is applied consist, first, of a drum, a, made to encircle the smoke-stack, and large enough to leave a flue between the outside of the smoke-pipe and the inside of the drum, the upper part of this drum being fitted with a series of vanes, a a, to collect the air in the drum when the pipe is in motion in either direction; second, a series of pipes, d d, fitted in the smoke-stack, the upper ends of which pipes are formed in a long angular nozzle, which is fitted over corresponding - shaped openings cut in the side of the smoke-pipe to create a passage or flue from the drum to the pipes. The said pipes pass down through the flues b of the steam-chimney, and connect to the horizontal pipes d', arranged in the smoke-connection H. These horizontal pipes d' run the whole length of the smoke-connection, by which all the boilers in the series are connected to the hot-air blast. Third, a series of pipes, f f, connecting the pipes d' to a pipe or pipes, i, set either in the furnace or arranged in the water-space of the boiler, as shown in Fig. 4, the pipes f being fitted with valves j, to regulate the flow of hot air, and the pipes i being fitted with a series of jet-pipes or holes, v, to diffuse the free air evenly over the surface of the fire, the jet-pipes to be screwed through the side plate of the furnace into the pipe in the manner shown, or they may be applied in any good and efficient manner to effect the end sought after.

It will be seen that by this arrangement the air is collected in the drum a and forced down the pipes d by the motion of the smoke-pipe in either direction; that the air is heated on its passage through the drum and pipes by the escaping or waste heat of the furnace, and that the furnace is kept supplied with a current or blast of hot free air without the ex-

penditure of any power or fuel beyond what is now consumed in the operation of the machinery of the vessel.

Having now described the nature and extent of my invention, I claim and desire to secure by Letters Patent—

The arrangement, substantially herein described, of the superheating-pipes and receiving-drum in relation to each other and to the furnace, smoke-connection, steam-chimney, or

smoke-pipe, for the purpose of collecting and forcing down the air by the motion of the vessel, and for the purpose of heating the same in its passage to the fire by the waste heat of the furnace, substantially in the manner described.

WM. C. FORD.
